UNITED STATES PATENT OFFICE.

JOHN RUMPF, OF NEW MILFORD BOROUGH, NEW JERSEY, ASSIGNOR TO THE SAFETY CAR HEATING & LIGHTING COMPANY, A CORPORATION OF NEW JERSEY.

PRESSURE REGULATOR.

Application filed February 24, 1923. Serial No. 620,923.

To all whom it may concern:

Be it known that I, JOHN RUMPF, a citizen of the United States, and a resident of borough of New Milford, county of Bergen, and State of New Jersey, have invented 5 an Improvement in Pressure Regulators, of which the following is a specification.

This invention relates to construction for pressure-regulating devices and the like.

10 One of the objects thereof is to provide a device of the above nature of simple and durable construction and well adapted to meet the requirements of hard practical use. Another object is to provide such a device 15 capable of a high degree of efficiency in service. Another object is to provide a device of the above nature wherein the parts are conveniently and easily assembled and are readily accessible for cleaning, replacement or repair. Other objects will be in 20 part obvious or in part pointed out hereinafter.

The invention accordingly consists in the features of construction, combinations of 25 elements and arrangements of parts as will be exemplified in the structure to be hereinafter set forth and the scope of the application of which will be indicated in the following claims.

30 In the accompanying drawing in which is shown one of the various possible embodiments of this invention,

Figure 1 is a plan of a pressure regulator, certain parts being omitted; and

35 Figure 2 is a sectional elevation, the section being taken substantially along the line 2-2 of Fig. 1.

Similar reference characters refer to similar parts in both views of the drawing.

40 Referring now to the drawing in detail, and first with reference particularly to Fig. 2, there is shown a member 10 forming the main or body portion of a casing, preferably formed of forged brass in order that the metal may be homogeneous and free 45 from porosity. On the inside of the casing 10 and adjacent its lower wall is formed an inwardly projecting boss 11 through which extends a passageway threaded at its outer 50 end 12 to receive a pipe connection from any desired source of fluid supply. Adjacent the central portion of this passage is positioned strainer felt or wicking 13, and on either side of this wicking is positioned 55 a member of straining gauze 13^a to strain

and purify the gas or other fluid admitted to the interior of the casing. Into the other end of this passage through the boss 11 is threaded a valve casing 14 provided with a restricted passage 15 opening into a larger 60 recess 16 at its inner side. Within this recess 16 loosely rests a valve member 17 provided with a conical end 18 adapted to cooperate with the inner end of the passage 15. The valve member 17 is provided 65 with a longitudinal recess 19 in which rests a strut 20 through which the valve is operated. The end of the valve member 17 is provided with a shoulder 17^a between which and the end of the casing 14 rests a coiled 70 spring 21 tending to draw the valve member 17 away from its seat about the end of the passageway 15.

The interior of the casing 10 forms a chamber 22, the upper side of which is closed 75 by a diaphragm 23 held in place between the top rim of the casing member 10 and a flanged ring 24 by screws such as 25. The central portion of the diaphragm 23 is clamped between a pair of washers 26 and 27 by means of a clamping bolt 28 passing therethrough and clamping nuts 29. The clamping bolt 28 is provided with a downwardly extending portion 30 of reduced 80 diameter through an opening 31 in which passes the end portion 32^a of the longer end of a substantially L-shaped lever 32. The upper and lower walls of the opening 31 are preferably rounded to permit of a 85 rocking motion of the lever 32.

90 The lever 32 extending toward the curved portion thereof is preferably gradually increased in width, as shown in Fig. 1, and adjacent the end portion of its shorter end is pivoted upon the ends of two cone-pointed screws 33 which are threaded through openings in the casing member 10 and are provided with locking nuts 34. The screws 33 are preferably of a length to reach only part way through the casing 10 and in the outer ends of the openings therefor are threaded screws 33^a between the heads of which and the outer surface of the casing 10 is inserted packing to insure a tight closure. Below the pivot points 33 the lever 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

the lever 32 and thus holds it in place between the lever and the valve member.

On either side of the strut 20 the lever 32 is likewise engaged by a pair of members 35 provided with pointed end portions 36 and serving as guides for the adjacent ends of a pair of coiled compression springs 37. The other ends of the springs 37 are provided with guide members 38 into the open ends 10 of which are inserted spring guide screws 39. These guide screws 39 are threaded tightly into the casing member 10 from the outside. Thus the compression springs 37 bearing against the lever 32, through the action of the lever 32 in engagement with the opening 31 in the member 30, tend to pull the diaphragm 23 downwardly in opposition to the pressure thereon of fluid within the chamber 22. By adjustment of the pivot 15 screws 33 the lever 32 may be moved away from or toward the springs 37 and the compression in the springs 37 may thus be varied at will.

The action of the pressure regulator is substantially as follows: Gas or other fluid under pressure enters through the passage-way 25 through the boss 11 and through the passage 15 past the valve 17 and into the chamber 22. Thereupon pressure builds up 30 within the chamber 22 bearing against the diaphragm 23 and tending to force the diaphragm upwardly. A movement upwardly of the diaphragm 23, through the lever 32 rocking upon its pivots 33 thrusts the strut 20 to the right and forces the valve member 17 toward closing position. Any movement upwardly of the diaphragm 23, however, is opposed by the pressure of the 35 springs 37 bearing against the lever 32. Thus, upon a pressure being built up within the chamber 22 which is greater than the combined force of the springs 37 opposing the movement of the diaphragm 23, the valve 17, through the movement of the lever 32 about its pivot and through the connecting 40 strut 20, will be moved to closed position arresting the further entrance of gas to the chamber 22. The exit passage from the chamber 22 is shown at 40 from which connection may be made to any desired point. Upon the pressure within the chamber 22 dropping below the pressure exerted by the 45 springs 37 upon the diaphragm 23 due to withdrawal of the fluid through the passage 50 40, the springs 37 will move the lever 32 back again and the valve 17 will be moved to open position. Thus it will be seen that there is automatically maintained a substantially constant gas pressure within the chamber 22. The amount of this constant pressure is regulated by the compression placed 55 in the springs 37 which may be set as desired, as above described, by adjustment of the pivot screws 33. The pivots for the lever 32 being pointed, as well as the ends of the

valve guides 35 and of the strut 20 engaging the lever 32, friction is substantially avoided thus greatly augmenting the sensitiveness and accuracy of the device as a whole. The valve mechanism is confined substantially 70 within the casing 14 so that machine work upon the outer casing itself is practically done away with. A removable cover member 41 rests upon the upper rim of the ring 24 to protect the diaphragm 23 from dust 75 and dirt.

It will thus be seen that there is herein provided a device which embodies the features of this invention, which device in its action attains the various objects of the invention, and that the same is well adapted to meet the requirements of practical use.

As many possible embodiments may be made of this invention and as many changes might be made in the embodiment herein set forth, it is to be understood that all matter hereinbefore set forth or shown in the accompanying drawing is to be interpreted as 85 illustrative and not in a limiting sense.

I claim as my invention:—

1. In a device of the class described, in combination, a pressure chamber, a valve controlling the entrance of fluid thereto, a diaphragm responsive to fluid pressure within said chamber, a lever connected to said diaphragm and responsive to movements thereof, means connecting said lever and said valve to make the latter responsive to movements of the former, spring means urging 90 said lever in opposition to the effect thereon of fluid pressure upon said diaphragm and holding said lever against its fulcrum, and means for adjusting the position of said fulcrum to vary the force exerted by said spring against said lever.

2. In a device of the class described, in combination, a pressure chamber, a valve controlling the entrance of fluid thereto, a diaphragm responsive to fluid pressure within said chamber, a lever connected to said diaphragm and responsive to movements thereof, a connecting member loosely resting between said valve and said lever to make the former responsive to movements of the latter toward the former, spring means urging 100 said lever in opposition to the effect thereon of fluid pressure against said diaphragm, and a second spring urging said connecting member against said lever.

3. In a device of the class described, in combination, a pressure chamber, a passage for the entrance of fluid thereto, a valve member loosely supported within said passage and adapted to control the flow of fluid therethrough, a diaphragm responsive to 110 fluid pressure within said chamber, a lever connected to said diaphragm and responsive to movements thereof, spring means urging 115 said diaphragm in opposition to the effect of fluid pressure thereon, a strut interposed be-

5 'tween said valve and said lever to make the former responsive to the movements of the latter toward the former, and a second spring means holding said strut in position between said valve and said lever.

10 4. In a device of the class described, in combination, a pressure chamber, a passage for the entrance of fluid thereto, a valve member loosely supported within said passage and adapted to control the flow of fluid therethrough, a diaphragm responsive to fluid pressure within said chamber, a lever connected to said diaphragm and responsive to movements thereof, spring means urging 15 said diaphragm in opposition to the effect of fluid pressure thereon, a strut interposed between said valve and said lever to make the former responsive to movements of the latter toward the former, and spring means bearing 20 against said valve member urging the latter away from its seat and holding said strut in position between said lever and said valve member.

25 5. In a device of the class described, in combination, a casing having an inlet passage and an outlet passage for fluid, a diaphragm closing one side of said casing and responsive to fluid pressure therein, a lever connected to said diaphragm to be responsive 30 to movements thereof and extending opposite said inlet passage, a valve controlling said inlet passage, means connecting said valve and said lever to make the former responsive to movements of the latter, and a 35 pair of spiral compression springs, one on either side of said inlet passage bearing against said lever in opposition to the effect thereon of fluid pressure upon said diaphragm and holding said lever in position 40 against its fulcrum.

45 6. In a device of the class described, in combination, a casing having an inlet passage and an outlet passage for fluid, a diaphragm closing one side of said casing and responsive to fluid pressure therein, a lever connected to said diaphragm to be responsive 50 to movements thereof and extending opposite said inlet passage, a valve controlling said inlet passage, means connecting said valve and said lever to make the former responsive to movements of the latter, a pivot for said lever, compression means interposed between said lever and the wall of 55 said casing urging said lever in opposition to the effect thereon of fluid pressure upon said diaphragm and urging said lever against said pivot, and means for adjusting the position of said pivot to vary the compression in said spring.

60 7. In a device of the class described, in

combination, a casing comprising a pressure chamber, and having in a wall thereof an inlet passage for fluid, a diaphragm closing one side of said chamber and responsive to fluid pressure therein, a lever connected 65 to said diaphragm to be responsive to movements thereof and extending opposite said inlet passage, a hollow member threaded into the inner side of said passage and comprising a valve seat, a valve member resting 70 loosely in said hollow member and adapted to coact with said valve seat to control said passage, a strut loosely interposed between said valve member and said lever to make the former responsive to movements of the 75 latter toward the former, a spring interposed between said hollow member and said valve, urging the latter toward said lever and away from said seat and holding said strut in position, spring means bearing 80 against said lever in opposition to the effect thereon of fluid pressure against said diaphragm, and means for adjusting the force exerted by said last means.

8. In a device of the class described, in combination, a casing comprising a pressure chamber and having in a wall thereof an inlet passage for fluid, a diaphragm closing one side of said chamber and responsive to the fluid pressure therein, a lever connected 90 to said diaphragm to be responsive to movements thereof and extending adjacent said inlet passage, a loosely mounted valve member adapted to coact with the inner side of said passage, means adapted to guide said valve member into operative relation with said passage, a member loosely interposed between said valve member and said lever to make the former responsive to movements of the latter toward the former, and spring 95 means urging said valve member away from said passage and holding said loosely interposed member in position.

9. In a device of the class described, in combination, a pressure chamber, a valve controlling the entrance of fluid thereto, a diaphragm exposed to fluid pressure within said chamber and responsive thereto, a lever connecting said diaphragm and said valve, a pivot for said lever mounted in a wall of said chamber, means for adjusting the position of said pivot, and adjustable means controlled by the adjustment of said pivot urging said lever in opposition to the effect thereon of said fluid pressure acting upon 105 110 115 said diaphragm.

In testimony whereof, I have signed my name to this specification this 13th day of February, 1923.

JOHN RUMPF,
